AMALGAMATOR

Ansel B. Hill, Seattle, Wash.

Application January 3, 1938, Serial No. 183,168

7 Claims. (Cl. 209—184)

The invention relates to an amalgamator and more especially to a gold saving or separating machine of the vertical type and mercury contained.

5 The primary object of the invention is the provision of a machine of this character, wherein the same is used in mill concentrates and wet or dry placer ground for the recovery of gold particles through mechanical action forcing and circulating the material through the mercury, which latter will readily amalgamate with the particles of gold and due to the specific gravities or the difference in the weight of the mercury and gold, the particles will precipitate into a receiver therefor and in this manner will be recovered.

10 Another object of the invention is the provision of a machine of this character, wherein the impeller having a constant speed and the material having a constant flow to the impeller holds a constant mercury level and through mechanical action gold particles can be recovered to avoid loss thereof and with dispatch, the waste being delivered from the machine automatically.

15 A further object of the invention is the provision of a machine of this character, wherein the amalgam unit can be readily cleaned and under mechanical action gold particles will be scrubbed, cleaned and polished.

20 A still further object of the invention is the provision of a machine of this character, which is simple in its construction, thoroughly reliable and efficient in operation, mechanical in the working thereof and inexpensive to manufacture and install.

25 With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

30 In the accompanying drawing:

Figure 1 is a vertical sectional view through a machine constructed in accordance with the invention.

Figure 2 is a plan view of one of the stationary amalgam disks or plates.

Figure 3 is a plan view of one of the revolving amalgam disks or plates.

Figure 4 is a plan view of an agitator and sand slinger employed in the machine.

Figure 5 is a top plan view of a spiral amalgamator unit employed in the machine.

35 Similar reference characters indicate corre-

sponding parts throughout the several views in the drawing.

Referring to the drawing in detail, A designates generally a portion of the machine constructed in accordance with the invention and involves a cylindrical body 10 having a hopper-like closed bottom 11 while the opposite upper end 12 is open and this body forms a holder for mercury, the level thereof within the said body being indicated at 13.

10 Centrally arranged within the body 10 for a distance of the upper portion is an impeller tube 14, which has its upper end projected above the mercury level 13 and into which leads a feed chute 15, while concentrically about this tube is 15 a series of superimposed spiral amalgam plates 16 effecting a plurality of spiral feed ways 17 by the spiral contour thereof. Each plate 16 has its center hub 18 which is of circular formation concentrically about the impeller tube 14.

20 Within the body 10 below the tube 14 are series of alternately arranged stationary and revolving disks 19 and 20, respectively, being alternately arranged with relation to each other and have formed therein vertically disposed holes 21 which 25 are tapered both at the top and bottom toward the middle as at 22 and 23, respectively. The stationary disks 19 are held at rest upon seating ears 24 through the medium of set screws 25, the ears being integrally formed with and project from the interior surface of the body 10. The disks 19 and 20 have their circular hubs 26 30 vertically aligned with each other and in register with the impeller tube 14 while the hubs of the revolving disks 20 interfit and have bearing in 35 the hubs of the stationary disks while the uppermost stationary disk 19 has created therein a seat for the lower end of the impeller tube 14.

30 Passing through the hubs 26 of the disks 19 and 20 are the spiral blades 27 of an impeller 40 splined or keyed at 28 with a power shaft 29 carried upwardly centrally through the tube 14 and journaled at 30 at its upper end outside of the body 10, being equipped with a power pulley 31 in association with a power source (not 45 shown). The hubs 26 of the rotary disks 20 are spoked at 32 with the impeller to rotate concurrently therewith while the hubs 26 of the stationary disks 19 are loose about the said impeller. The shaft 29 at its lower end has fixed thereto a 50 bladed agitator and sand slinger 33 operating within the mercury chamber 34 created at the lower hopper end 11 in the body 10, this hopper end being in communication with a gold particle or precious metal tubular receiver 35 equipped 55

with the hand operated cut-off valves 36 and 27, respectively, which are spaced apart to regulate the reception of the particles and the discharge thereof to and from the receiver 35.

5. In communication with the upper open end 12 of the body 10 is a discharge chute 38 which delivers the waste from the body 10 outside of the impeller tube 14 therein.

The upper faces of the revolving disks 20 have 10 formed thereon centripetal ridges 39 while the under faces of these disks at the perimeters thereof are provided with annular lips 40 effective to prevent material from being thrown past the outside rim thereof while the centripetal ridges 15 39 overcome the centrifugal action set up by the revolving disks 20.

The plates 16 are made from copper and the body 10 is made from cast metal.

In the operation of the machine the material 20 is fed into the impeller tube 14 and is forced downwardly by the impeller mechanically rotating and driven by the shaft 29, the blades 27 of said impeller being possessed of a right hand pitch and revolve in a left hand direction.

25 The material is forced into the chamber 34 at the lower hopper end 11 and thence through the coaction of the disks 19 and 20 the said material works upwardly through the holes 21, the combined agitator and sand slinger 33 acting

30 to agitate and equally distribute through the mercury within the body 10 and on its upward course. The material rises due to its difference in weight and the weight of the mercury while the lower taper 23 of the holes in the disks 19 and 20 aids in focusing the material to and through the holes while the taper 22 at the top of the latter causes the material to spread out and scatter through the mercury. This taper 22

40 at the top of the holes also allows the gold particles held in the mercury while in the state of agitation to settle to the bottom of the body 10 when the machine comes to a standstill. The annular lips 40 at the under side of the rotary disks 20 prevent the material from being thrown

45 past the outside rims of these disks while the ridges 39 overcome the centrifugal action caused by the disks 20 revolving, these disks 19 and 20 in cooperation function as an impeller in the upward flow of the mercury within the body 10

50 and the copper plates 16 in their spiral contour cause the material to rub and bear on the surfaces thereof during the upward course of the material and effect the gold particles to amalgamate with the mercury and adhere to these plates 16. The spiral plates 16 also serve the purpose of preventing the material from carrying particles of mercury with it by checking the velocity of such material while the spiral formation of these plates being such to cause the material to move in nearly a horizontal direction when leaving the mercury, the waste materials being floated upwardly and over the top of the body 10 for discharge therefrom through

55 the chute 38.

What is claimed is:

1. A machine of the kind described comprising a vertically disposed cylindrical body having a hopper-like bottom, a valved receiver opening 70 through the hopper-like bottom at the lowermost portion thereof, an impeller tube arranged within the upper portion of said body, superposed spiral amalgam plates about said tube and effecting a spiral way concentrically of the latter, series of alternately arranged stationary and

5 revolving disks below said tube and having vertically disposed holes tapered at the top and bottom toward the middle thereof, means within the body for the seating of the stationary disks therein, circular hubs formed with the disks in alignment with the impeller tube and interfitting with each other, and means extended through the said tube and having connection with the revolving disks for imparting rotation thereto.

2. A machine of the kind described comprising 10 a vertically disposed cylindrical body having a hopper-like bottom, a valved receiver opening through the hopper-like bottom at the lowermost portion thereof, an impeller tube arranged within the upper portion of said body, superposed spiral amalgam plates about said tube and effecting a spiral way concentrically of the latter, 15 series of alternately arranged stationary and revolving disks below said tube and having vertically disposed holes tapered at the top and bottom toward the middle thereof, means within the body for the seating of the stationary disks therein, circular hubs formed with the disks in alignment with the impeller tube and interfitting with each other, means extended through the 20 said tube and having connection with the revolving disks for imparting rotation thereto, and a feed chute opening into the said tube at the top of the body.

3. A machine of the kind described comprising 30 a vertically disposed cylindrical body having a hopper-like bottom, a valved receiver opening through the hopper-like bottom at the lowermost portion thereof, an impeller tube arranged within the upper portion of said body, superposed spiral amalgam plates about said tube and effecting a spiral way concentrically of the latter, 35 series of alternately arranged stationary and revolving disks below said tube and having vertically disposed holes tapered at the top and bottom toward the middle thereof, means within the body for the seating of the stationary disks therein, circular hubs formed with the disks in alignment with the impeller tube and interfitting with each other, means extended 40 through the said tube and having connection with the revolving disks for imparting rotation thereto, and a feed chute opening into the said tube at the top of the body, and a discharge chute having a portion about the upper part of said 45 body and communicative with the latter at its top.

4. A machine of the kind described comprising 50 a vertically disposed cylindrical body having a hopper-like bottom, a valved receiver opening 55 through the hopper-like bottom at the lowermost portion thereof, an impeller tube arranged within the upper portion of said body, superposed spiral amalgam plates about said tube and effecting a spiral way concentrically of the latter, 60 series of alternately arranged stationary and revolving disks below said tube and having vertically disposed holes tapered at the top and bottom toward the middle thereof, means within the body for the seating of the stationary disks therein, circular hubs formed with the disks in alignment with the impeller tube and interfitting with each other, means extended 65 through the said tube and having connection with the revolving disks for imparting rotation thereto, a feed chute opening into the said tube at the top of the body, a discharge chute having a portion about the upper part of said body and communicative with the latter at its top, and a bladed agitator rotatably operated by said 70 75

means and within the hopper-like bottom for said body.

5. A machine of the kind described comprising a vertically disposed cylindrical body having a hopper-like bottom, a valved receiver opening through the hopper-like bottom at the lowermost portion thereof, an impeller tube arranged within the upper portion of said body, superposed spiral amalgam plates about said tube and effecting a spiral way concentrically of the latter, series of alternately arranged stationary and revolving disks below said tube and having vertically disposed holes tapered at the top and bottom toward the middle thereof, means within the body for 10 seating of the stationary disks therein, circular hubs formed with the disks in alignment with the impeller tube and interfitted with each other, means extended through the said tube and having connection with the revolving disks for imparting rotation thereto, a feed chute opening into the said tube at the top of the body, a discharge chute having a portion about the upper part of said body and communicative with the latter at its top, a bladed agitator rotatably operated by said means and within the hopper-like bottom for said body, and a mercurial column within the body and having a level above the amalgam plates.

6. A machine of the kind described comprising a vertically disposed cylindrical body having a hopper-like bottom, a valved receiver opening through the hopper-like bottom at the lowermost portion thereof, an impeller tube arranged within the upper portion of said body, superposed spiral amalgam plates about said tube and effecting a spiral way concentrically of the latter, series of alternately arranged stationary and revolving disks below said tube and having vertically disposed holes tapered at the top and bottom toward the middle thereof, means within the body for the seating of the stationary disks therein, circular hubs formed with the disks in alignment with the impeller tube and interfitted with each

other, means extended through the said tube and having connection with the revolving disks for imparting rotation thereto, a feed chute opening into the said tube at the top of the body, a discharge chute having a portion about the upper part of said body and communicative with the latter at its top, a bladed agitator rotatably operated by said means and within the hopper-like bottom for said body, a mercurial column within the body and having a level above the amalgam plates, and centripetal ridges formed at the upper faces of the revolving disks.

7. A machine of the kind described comprising a vertically disposed cylindrical body having a hopper-like bottom, a valved receiver opening through the hopper-like bottom at the lowermost portion thereof, an impeller tube arranged within the upper portion of said body, superposed spiral amalgam plates about said tube and effecting a spiral way concentrically of the latter, 20 series of alternately arranged stationary and revolving disks below said tube and having vertically disposed holes tapered at the top and bottom toward the middle thereof, means within the body for the seating of the stationary disks therein, 25 circular hubs formed with the disks in alignment with the impeller tube and interfitted with each other, means extended through the said tube and having connection with the revolving disks for imparting rotation thereto, a feed chute opening 30 into the said tube at the top of the body, a discharge chute having a portion about the upper part of said body and communicative with the latter at its top, a bladed agitator rotatably operated by said means and within the hopper-like 35 bottom for said body, a mercurial column within the body and having a level above the amalgam plates, centripetal ridges formed at the upper faces of the revolving disks, and annular lips depending from the under faces of said revolving 40 disks at the perimeters thereof.
